CANOPY

Raffaele M. De Leo, 1384 Massachusetts Ave.,
Cambridge, Mass.

Filed Dec. 21, 1962, Ser. No. 72,921

Term of patent 14 years

(Cl. D13—1)

FIG. 1 is a perspective front view of my new canopy design;

FIG. 2 is a plan view of the canopy shown in FIG. 1;

FIG. 3 is a right-side elevational view of the canopy shown in FIG. 4; and

FIG. 4 is a rear elevational view of the canopy shown in FIG. 1.

I claim:

The ornamental design for a canopy, as shown.
